GREASE APPLICATOR

Eric Le Cheminant, 47-49 Henderson St., Turrella,
New South Wales, Australia

Filed Mar. 15, 1971, Ser. No. 124,635

Term of patent 7 years

Int. Cl. D8—05

U.S. Cl. D52—2 A

Des. 226,591

PAGE 2

FIG. 3

FIG. 1 is a perspective view of the grease applicator viewed from above;

FIG. 2 is a perspective view thereof viewed from the underside of the drum attachment of the grease applicator and showing the grease gun component thereof in elevation; and

FIG. 3 is a plan view of the grease applicator.

I claim:

The ornamental design for a grease applicator, substantially as shown.
